UNITED STATES PATENT OFFICE.

WILLIAM A. SUTTON, OF NEW YORK, N. Y.

SKATE.

SPECIFICATION forming part of Letters Patent No. 236,276, dated January 4, 1881.

Application filed December 3, 1879.

To all whom it may concern:

Be it known that I, WILLIAM A. SUTTON, of the city, county, and State of New York, have invented certain new and useful Improvements in Skates, of which the following is a specification.

In the accompanying drawings, Figure 1 represents a sectional side elevation of my improved skate; Fig. 2, a bottom view with parts broken away; and Fig. 3 a vertical transverse section of the same on line *x x*, Fig. 2.

Similar letters of reference indicate corresponding parts.

This invention relates to such improvements in the skates generally known as "club-skates" that they can be secured to the sole and heel with greater facility and dispatch, and in a more reliable manner; and the invention consists in providing one of the adjustable sole-clamps and the heel-clamp with auxiliary adjusting devices, by which, when the clamps are once set to the proper size of shoe, the quick and rigid attachment of the skate to the sole and heel is obtained, as will appear more fully hereinafter.

Referring to the drawings, A represents a skate; B, the sole-plate, and C the heel-plate, of the same.

The sole-plate B is provided with transversely-sliding sole-clamps D, which are jointly moved by a right-and-left-hand screw, D', that connects the guide-plates D² of the clamps in the well-known manner. The guide-plates D² slide by means of slots a and fixed pins or studs a', with enlarged heads, at the under side of the sole-plate.

The heel-plate C is provided with fixed clamps or checks E and an adjustable clamp, E', which is guided in the slotted heel-plate C and set to the heel by a screw, E².

The skates of this construction are attached to the sole and heel of the boot or shoe by means of a key, which is applied to the square ends of the set-screws D' and E², the set-screws requiring for the rigid connection of the skate and shoe the application of considerable power, especially when after some use the parts should get rusty. To avoid this objection and facilitate the application of the skate so as to be easier handled, even by ladies, one of the sole-

clamps D and the heel-clamp E' are provided with auxiliary adjusting devices, by which these clamps are made independent and separately movable on their respective guide-plates, and actuated, after adjustment by the set-screws, by independent cam-levers F F'. For this purpose one of the sole-clamps and the heel-clamp are arranged with shanks b b', which are guided by slots and pins on the main guide-plates. The cam-levers F F' are eccentrically pivoted, the cam-lever F of the sole-clamp being connected by a circular slot, d, to the stud d' of the shank b of the movable sole-clamp D, while the cam-lever F' of the heel-clamp is pivoted to the fixed stud e of the main guide-plate e' of the heel-clamp E', and arranged to engage with its cam the raised clamp portion E' and a fixed stud, e², on the shank b' of the heel-clamp, so as to govern the forward and backward motion of the heel-clamp. This cam-lever connection may, however, be also made in a different manner, provided that one of the sole-clamps and the heel-clamp obtain their final adjustment to the sole and heel by the auxiliary lever devices.

The auxiliary adjusting mechanism has the advantage that the clamps may be set once for all to the size of the shoe, so as to require no adjustment when the skate is put on, while the final clamping action is imparted by throwing the cam-levers into the longitudinal position of the skate, as shown in Fig. 1, which can be accomplished without the least difficulty, so that an almost instant and positive attachment of the skate to the boot or shoe is obtained.

Having thus described my invention, I claim as new and desire to secure by Letters Patent—

1. In a skate provided with adjustable sole and heel clamps, the combination of the adjustable guide-plate D² with a sliding sole-clamp, D, guided thereby, and with a cam-lever, F, pivoted to the guide-plate and connected to the shank of the sole-clamp, so as to produce the final adjustment of the sole-clamp, substantially as set forth.

2. The combination, in a skate, of a heel-clamp consisting of two parts connected and adapted to move together and independently

of each other, and both movable on the heel-plate C, an adjusting device supported by the heel-plate to bear upon one part of said clamp, and an adjusting device whereby one part of
5 said clamp may be moved upon the other, substantially as set forth.

In testimony that I claim the foregoing as

my invention I have signed my name, in presence of two witnesses, this 25th day of November, 1879.

WM. A. SUTTON.
